DESIGN FOR A DISPENSER FOR VOLATILE LIQUIDS

Charles L. Gebauer, Cleveland, Ohio, assignor to
The Gebauer Chemical Company, Cleveland,
Ohio, a corporation of Ohio

Application February 25, 1937, Serial No. 67,858

Term of patent 14 years

To all whom it may concern:

Be it known that I, Charles L. Gebauer, a citizen of the United States, residing at Cleveland, in the county of Cuyahoga and State of Ohio, have invented a new, original, and ornamental Design for a Dispenser for Volatile Liquids, of which the following is a specification, reference being had to the accompanying drawing, forming part thereof, wherein

Fig. 1 is a side elevational view of a dispenser for volatile liquids showing my new design; and Fig. 2 is a top plan view thereof.

I claim:

The ornamental design for a dispenser for volatile liquids substantially as shown.

CHARLES L. GEBAUER.
